G. W. Tolman

UNITED STATES PATENT OFFICE.

GEORGE W. TOLEMAN, OF AUGUSTA, KENTUCKY.

IMPROVEMENT IN ROTARY HARROWS.

Specification forming part of Letters Patent No. 23,962, dated May 10, 1859.

To all whom it may concern:

Be it known that I, GEORGE W. TOLEMAN, of the city of Augusta, county of Bracken, and State of Kentucky, have invented an Improved Rotary Harrow; and I do hereby declare the following to be a full and exact description thereof, reference being had to the annexed drawing, and to the letters and figures marked thereon, making a part of the same.

The nature of this invention consists of an arrangement of devices, hereinafter described.

The center of the wood frame is made secure by means of the cast plates, which are bolted to the wood frame. (See drawing.) The arms of the frame are bolted to the iron circle No. 1 at each crossing of the same. A cast-iron shaft, No. 3, is elevated above, having a journal on the lower end, which passes through the center of the harrow. To this shaft is attached the draft-rod, made of rod-iron, which is fastened to the shaft by means of a nut at D, and passing from the draft-rod to the top of the shaft at D is an iron rod, C, used to regulate the harrow. There is attached to the same shaft and at right angles with the draft-rod a rod, B, of iron, to which is fastened the iron ball or roller No. 2, which roller or ball

rests on the circle-iron No. 1; and passing from this rod, to which the roller or ball is attached, there is an iron rod or hook, 4, extending to the draft-rod B to hold the rods B' the more securely to their place. Rotation is produced by means of the roller or ball No. 2, resting on the circle-iron 1, causing the teeth of the harrow on that side to sink deeper into the ground, thereby meeting with more resistance, and causing it to rotate as the harrow is drawn along.

I do not claim to be the inventor of the rotary principle of the harrow, for I am aware that they have been in use in various forms. I am also aware that balls or rollers have been used as assistant means of rotation; but,

Having thus described my invention, what I claim as new, and desire to secure by Letters Patent, is—

The arrangement of the frame A, shaft 3, iron circle 1, roller 2, rods B B' C, and rod or hook 4, operating conjointly, as set forth, for the purposes specified.

GEORGE W. TOLEMAN.
